UNITED STATES PATENT OFFICE.

ALFRED H. STEVENSON, OF CHUNCHULA, ALABAMA.

RAIL-JOINT.

SPECIFICATION forming part of Letters Patent No. 787,544, dated April 18, 1905.

Application filed July 29, 1904. Serial No. 218,708.

To all whom it may concern:

Be it known that I, ALFRED H. STEVENSON, a citizen of the United States, residing at Chunchula, in the county of Mobile and State of Alabama, have invented new and useful Improvements in Rail-Joints, of which the following is a specification.

This invention relates to rail-joints.

The principal object of the invention is to avoid the necessity of perforating the fish-plates and rails and of using bolts extending through the fish-plates and rails for holding the joint in assembled position.

Further objects of the invention are generally to improve and simplify the construction of rail-joints.

With the foregoing and other minor objects in view, which will appear as the description proceeds, the invention resides, essentially, in a rail-joint comprising a chair having two parallel walls, one of the walls being formed with internal projections and the other wall having reinforced portions formed with perforations opposite the projections, adjusting-screws passing through the perforations, and fish-plates upon opposite sides of the rails, each fish-plate having reinforced portions formed with depressions, the depressions of one plate receiving the internal projections and the depressions of the other plate receiving the adjusting-screws.

The invention also resides in the particular combination and arrangement of parts and in the precise details of construction hereinafter described and claimed as a practical embodiment of the invention.

In the accompanying drawings, forming part of this specification, Figure 1 is a perspective view of a rail-joint constructed in accordance with the invention. Fig. 2 is a plan view thereof. Fig. 3 is a perspective view of the chair. Fig. 4 is a side elevation of one of the fish-plates. Fig. 5 is a transverse vertical section through the rail-joint adjacent to one of the adjusting-screws.

Like reference-numerals indicate corresponding parts in the several views.

The reference-numeral 1 indicates the base of the chair, which is formed with side flanges 2 to facilitate its application to the sleepers

of the road-bed. The chair 1 is formed with two parallel walls 3 and 4', the wall 3 being thickened or enlarged at its upper end, as shown at 4, to increase its strength and having internal projections 5 thereon, and the wall 4' having reinforced portions 6 extending upwardly from the base of the chair in order to strengthen the wall 4' against the lateral strain placed thereon. Formed integrally upon each of the reinforcing portions 6 of the wall 4' is a bearing-nut 7, through which extends an adjusting-screw 8, said adjusting-screw extending also through the reinforcement 6 and wall 4'.

Fish-plates, such as 9, are placed against opposite sides of the rails 10 and 11, as usual. Each of the fish-plates 9 is formed with a pair of inclined flanges 12 and 13, which bear, respectively, against the under side of the head of the rail and against the upper side of the base thereof, as shown. Intermediate the inclined flanges 12 and 13 each of the fish-plates is formed with a plurality of reinforcing portions 14, each reinforcing portion being preferably of pyramidal shape and having therein a depression, such as 15. The depressions of one of the fish-plates receive the internal projections 5 of the wall 3, as shown in Fig. 5, and the depressions of the other fish-plate receive the inner rounded ends 80 of the adjusting-screws 8, whereby the rail ends are clamped securely in position upon the chair without the necessity of perforating the fish-plates or rails and of using bolts or the like extending through the fish-plates 85 and rails to hold the joint in assembled condition. If desired, one or both of the upper inclined flanges 12 of the fish-plates may be cut off, as shown at 16, in order to prevent said flanges from projecting outwardly beyond 90 the head of the rail.

In its particular combination and arrangement of parts and in its precise details of construction the rail-joint of this invention constitutes an improvement over prior devices of a similar character.

Having thus described the invention, what is claimed as new is—

1. A rail-joint, comprising a chair having two parallel walls, one of the walls having

internal projections, and the other wall having reinforced portions formed with perforations opposite the internal projections, adjusting-screws passing through the perforations, and 5 fish-plates upon opposite sides of the rails, each fish-plate having reinforced portions formed with depressions, the depressions of one fish-plate receiving the internal projections of one wall, and the depressions of the 10 other fish-plate receiving the adjusting-screws of the other wall.

2. A rail-joint, comprising a chair having side flanges and two parallel walls, one of the walls being thickened or enlarged at its upper 15 end and having internal projections, and the other wall having reinforced portions extending upwardly from the base of the chair and formed with perforations opposite the inter-

nal projections, said reinforced portions having integral bearing-nuts thereon, adjusting-screws passing through the bearing-nuts, reinforced portions and wall, and fish-plates upon opposite sides of the rails, each fish-plate having inclined flanges and pyramidal-shaped reinforcing portions located between 2 the inclined flanges and formed with depressions, the depressions of one plate receiving the internal projections of one wall and the depressions of the other plate receiving the adjusting-screws of the other wall. 3

In testimony whereof I affix my signature in presence of two witnesses.

ALFRED H. STEVENSON.
